UNITED STATES PATENT OFFICE.

ANDREW HOHNER, OF OTTAWA, ILLINOIS.

GRADER AND CLEANER FOR GRAIN, BEANS, &c.

No. 898,892.

Specification of Letters Patent. Patented Sept. 15, 1908.

Application filed March 26, 1908. Serial No. 423,410.

To all whom it may concern:

Be it known that I, ANDREW HOHNER, a citizen of the United States, residing at Ottawa, in the county of LaSalle and State of Illinois, have invented certain new and useful Improvements in Graders and Cleaners for Grain, Beans, &c.; and I do hereby declare the following to be a full, clear, and exact description of the invention, such as will enable 10 others skilled in the art to which it appertains to make and use the same.

This invention relates to new and useful improvements in machines for grading and cleaning grain or the like and is intended 15 more especially to be employed with corn, beans, peas, etc.

It is an object of the invention to provide a novel device of this character which will not only thoroughly clean the substance acted 20 thereupon, but will grade the same according to the size of the particles constituting the substance.

It is also an object of the invention to provide a novel device of this character which 25 can be employed in conjunction with a sheller, the combination between the two being such as to have the grading or cleaning device operated from the sheller.

It is also an object of the invention to provide 30 a novel device of this character comprising a rotatable cylinder, said cylinder being provided with means for partially elevating the substance, the cleaning and grading being attained by the agitation of the substance.

35 It is a still further object of the invention to provide a novel device of this character which will be simple in construction, efficient in practice and comparatively inexpensive to manufacture.

40 With the above and other objects in view the invention consists of the details of construction and in the novel arrangement and combination of parts to be hereinafter referred to.

45 In describing the invention in detail reference will be had to the accompanying drawings forming part of this specification wherein like characters of reference denote corresponding parts in the several views, and in 50 which,

55 Figure 1 is a longitudinal sectional view illustrating the invention. Fig. 2 is a cross section looking in the direction of the head of the machine, and, Fig. 3 is a fragmentary view in perspective of one of the ribs of the

cylinder employed in conjunction with the invention.

In the drawings 1 denotes a frame preferably rectangular, arranged on an incline and held at one end by an approximate U-shaped support 3, the bend 4 of the support being above the frame. The frame is held against displacement and reinforced by the diagonal or inclined straps 5 arranged at each side of the frame, one end of each strap being secured 60 to the frame 1 and the opposite end to the support 3. The upper end of the frame is supported by an upright 6 arranged on each side of the frame and projecting a distance thereabove. Each of the uprights 6 is provided with a bracing or reinforcing strip 7 also arranged on an incline and having one end secured to the frame 1 and the opposite end secured to the upright 6. 70

The portions of the uprights 6 above the frame 1 have secured thereto a vertically arranged frame 8 which supports a sheller mechanism. This sheller comprises a toothed disk 9 and is fixed to a shaft 10 mounted within a bearing 11 carried by the frame 8. 80 This disk has secured to its outer face a hand-crank 12 by which the same is rotated.

Opposed to the toothed disk 9 to one side of its center is a vertically arranged concave 13 of any desired or preferred construction. 85

As the specific structure of the sheller forms no essential feature of the invention a detail thereof is believed to be unnecessary, except to state that the shaft projects beyond the bearing 11 and has fixed on its 90 inner end a pulley or grooved wheel 14. It is also well to state that the frame 8, hereinbefore referred to is further supported by the upper edge portion of a supply hopper 15 fixed to the upper portion of the uprights 6. 95

A portion 16 of the frame 8 projects downwardly and is secured to the front end of the frame 1, and mounted in this depending portion and in a bearing 17 secured to the inner surface of the bend 4 of the support 3 approximately centrally thereof is a shaft 18. On this shaft 18 in proximity to the bearing 17 and the hopper 15 hereinbefore referred to are spiders 19 and 20, and these spiders are connected by longitudinally disposed spaced 100 ribs 21 held to the spiders 19 and 20 adjacent their free end portions by clamping rims 22 and 23. The clamping rim 22 is positioned directly beneath the pulley 14 hereinbefore referred to and is grooved for the recep- 110

tion of an endless flexible member 24 which engages the rim 22 and passes over the pulley 14.

It will thus be seen that with the rotation 5 of the shaft 10 the cylinder formed by the spiders 19 and 20 and the ribs 21 will be rotated. As the cylinder is of much greater diameter than the diameter of the pulley 14 the cylinder will, of necessity, rotate at a less 10 speed than the speed or rotation of the pulley 14.

The spider 19 has secured to its inner surface a flange 25 which projects outwardly beyond the spider 19 and has its free portion 15 26 bent inwardly.

The hopper 15 hereinbefore referred to is provided adjacent its lower end with a chute 27 which projects within the flange 26 and is intended to discharge the substance falling 20 within the hopper 15 within the cylinder. To expedite this discharge and to permit the passage of the shaft 18 the inner wall of the hopper 15 adjacent the flange and above the chute 27 is cut away as at 28.

25 It might be well to state at this point that the rear wall of the hopper 15 is provided with a perforation for the passage of the shaft 18.

As shown in Fig. 1 it is to be observed that 30 a portion of the ribs adjacent the upper end thereof are in close proximity as indicated at 29 and that for a second length they are arranged a greater distance apart as at 30 and that at a point adjacent the lower end or the 35 spider 20 they are further spaced as at 31. This arrangement is provided to permit the grading of the substances discharged within the hopper. Supposing the substance to be beans, they are fed within the cylinder 40 through the hopper 15 and the smaller of the beans will fall between the space 29 and drop within a discharge hopper 32 therebeneath. The larger beans will be discharged through the spaces 30 and those of 45 a certain size will be discharged through the spaces 30 to the hopper 33 therebeneath, while the largest sizes will be carried to the lower end of the cylinder and discharged through the openings 31 to the hopper 34.

50 An edge of each rib 21 within the portion 29 is notched as at 35 as shown in Fig. 1 and in detail Fig. 5. It is also to be observed that the inner face of the rib adjacent each

notch is provided with a concave recess 36. This is to permit the ready passage of small 55 rounded particles. It is also to be stated that each of the ribs 21 is triangular in cross-section, also disclosed in Fig. 3, and that the inclines of the faces extend in one direction. The cylinder rotates in such a direction as 60 to bring the base 37 of each rib in advance of the movement of the cylinder. This will cause the ribs to elevate the grain until the rib has made about a one-half rotation when the particles will drop to the base of the 65 cylinder. It is this agitation that causes the particles to pass through the various spaces.

In order to hold the ribs against spreading intermediate their length an auxiliary rim 70 38 is interposed around the cylinder at a predetermined point between the rims 22 and 23. The chutes 32, 33 and 34 are each secured to the base of a body 39 having its longitudinal sides inclined as shown in Fig. 2. This body may be supported beneath the 75 cylinder in any desired manner, but it has been found best to give each free edge portion of the body an angular bend 40 to engage the frame 1.

Attention is also directed to the fact that 80 the hopper 15 projects at one side a distance beyond the sheller mechanism hereinbefore referred to in order to permit the grain or other particles being inserted within the hopper without the necessity of the same 85 passing through the sheller mechanism.

What I claim is:

A grader of the class described, comprising a frame and a cylinder rotatably held thereby, said cylinder including a plurality of 90 longitudinal ribs, said ribs being spaced one from the other, the space between each succeeding rib being increased at intervals by stepping one of the opposed edges of the ribs, each rib being triangular in cross section, the 95 broadest portion of each rib having notches in an edge thereof, each notch being in alignment with a concave recess in a face of the rib.

In testimony whereof I have signed my 100 name to this specification in the presence of two subscribing witnesses.

ANDREW HOHNER.
